ROPE-SPlicing DEVICE
 Levi Clark Beveridge, 123 Ann St.,
 Beaufort, N.C. 28516
 Filed Sept. 28, 1964, Ser. No. 399,491
 10 Claims. (Cl. 57—23)

This invention relates to rope-splicing devices, and has for its principal object the provision of an improved rope-splicing device possessing both greater versatility and greater facility of utilization than the splicing needles and similar implements heretofore known.

Related and more specific objects of this invention are the provision of the rope-splicing device which is self-supporting so as to leave free both hands of the user, and which is capable of being employed to splice rope of many different sizes. In the latter connection, a single device embodying principles of the present invention may be employed without modification to splice ropes ranging in size from the very smallest to the very largest now in general use.

Another more specific object is provision of a rope-splicing device which is so designed and constructed as to permit a user to effect the splicing operation with a minimum expenditure of time and effort.

Still another object is provision of a device of the type described which is readily portable, and which is of compact, sturdy, long-lasting and economical construction.

Still other objects and advantages will be in part evident and in part pointed out hereinafter in the following description of an illustrative embodiment of the invention, which should be read in conjunction with the accompanying drawing, in which:

FIGURE 1 is a front perspective view of a device embodying the invention being used to splice a rope;

FIGURES 2 and 3 are enlarged front perspective and top plan views, respectively, of the device of FIGURE 1;

FIGURE 4 is an enlarged front perspective view of the top portion of the device of FIGURE 1, with the rope being spliced impaled thereon; and

FIGURE 5 is an enlarged horizontal section taken through the top portion of the device of FIGURE 1, with the rope being spliced impaled thereon.

Referring more specifically to the drawings, the device there shown consists generally of a self-supporting tripod-type base member 10 upon which a spike member 12 is mounted in a generally upright position. All of the components of the device, including members 10, 12, are constructed of steel or other sturdy, wear-resistant material possessing similar properties.

Base member 10 includes elongate legs 14, 16 and 18, and a cross-bar 20. A pivot pin 22 extends through and interconnects the lower end portion of leg 18 and the center of cross-bar 20. As is shown in the drawings, when the rope-splicing device is in use cross-bar 20 extends normal to leg 18 and lies horizontally upon the ground or other supporting surface present at the site of the splicing operation. However, when it is desired to render the device more compact for storage or transportation, cross-bar 20 may be pivoted from its illustrated position through an arc of ninety degrees and to a position parallel with the leg 18 to which it is connected by pin 22.

Spike member 12 of the device consists of two flat wall sections 24, 26 integrally joined together along a common edge 28 so as to include an angle of approximately ninety degrees therebetween. Spike member 12 is tapered, the upper end 30 thereof being pointed and the free edges 32, 34 of wall sections 24, 26, respectively, as well as edge 28, diverging downwardly from such pointed upper end along their entire lengths. While periph-

2

eral edge 28 of spike member 12 may be straight, the edges 32, 34 bordering the open space between walls 24, 26 of spike member 12 are convexedly curved, as shown, for reasons subsequently made apparent. As is best shown in FIGURE 5, spike member 12 has a generally V-shaped configuration in horizontal cross-section, and the previously-mentioned open space between walls 24, 26 and edges 32, 34 thereof defines a passageway 36 extending along its entire length or height. Due to the tapered construction of the spike member, it will be apparent that passageway 36 possesses an increasing cross-sectional area from the pointed upper end 30 to the lower end of spike member 12.

When spike member 12 is constructed from a suitably machined conventional angle section, as in the case of the illustrated embodiment of the device, leg 18 of base member 10 may be formed integrally therewith as a reduced-size extension of such angle section. Apart from other benefits, this construction results in leg 18 of base member 10 being alined with edge 28 of spike member 12, which alinement is a significant feature of the present invention. Similarly, legs 14, 16 of base member 12 are connected to spike member 12 in such a manner that when the device is in use these legs are alined with and in effect form extensions of edges 32, 34, respectively, of the spike member. The specific connection between legs 14, 16 and spike member 12 consists of pivot pins 38, 40 which respectively extend through the upper ends of the former and through wall sections 24, 26 of the latter at points adjacent the lowermost extremities of edges 32, 34 thereof. The pivotal mounting of legs 14, 16 is such as to permit the same to be swung inwardly toward fixed leg 18 when the device is not in use, so as to thus facilitate the device's transportation and/or storage.

A significant advantage of the present device is that it leaves both hands of a user free to manipulate the rope being spliced. Thus, when erected for use as shown in the drawing, the device is completely self-supporting and is quite stable. In the latter connection, it will be noted that all of the legs of base member 10, and therefore all of the edges of spike member 12 alined therewith, extend at an angle relative to the vertical axis of the device. It will also be noted that the stabilizing effect of cross-bar 20 of base member 10 can be enhanced, as illustrated in FIGURE 1, by the user placing his feet thereon as the splicing operation is performed. As is also illustrated in FIGURE 1, the height of the device is such that the splicing operation can be performed 50 while the user is in a seated position.

The splicing operation is initiated by the user grasping in both hands that length of the rope in which the splice is to be made, and impaling the same upon pointed upper end 30 of spike member 12. The impaled length of rope 55 is then moved downwardly of the spike member by the user until the rope is opened, by the diverging edges 28, 32, 34, to such an extent that a desired one of its end strands S can be passed through passageway 36 and between the separated strands S' of the impaled length (see FIGURE 5). After one of the strands S has been passed through 60 passageway 36 as shown in FIGURES 4 and 5, the free end thereof is pulled downwardly and to the right, as illustrated by the arrow of FIGURE 5. This brings the strand S into snug, intimate engagement with the junction of the strands S' adjacent edge 34 of spike member 12, thereby producing, as the foregoing operation is repeated, an exceptionally smooth and tight splice.

Since spreading or opening up the impaled rope as the same is moved downwardly of spike member 12 is produced by the downwardly-diverging edges 28, 32, 34 at the periphery thereof, and since these edges are of rela-

tively small width, the areal contact and therefore the friction between the rope and spike 12 are appreciably less than in the case of a generally cylindrical splicing device such as a conventional marlinspike. A significant advantage of the present device, therefore, is that only a minimal amount of the force is necessary to effect the desired opening up of the impaled rope. An additional advantage is the degree of opening up of the rope which is achieved in relation to its downward movement. In comparison with known splicing implement, only a small amount of movement of the rope downwardly of spike member 12 is necessary to sufficiently open up or spread the latter. This desirable result is due not only to spike member 12 having three mutually-diverging edges which effect the spreading or opening of the rope, but also to two of these edges, 32 and 34, being convexedly curved rather than straight, as previously described.

Ropes of any size ranging from the smallest to the largest now in general use may be spliced by the present device. When splicing very small rope, it is necessary to move the same downwardly of spike member 12 to a location only a slight distance below pointed upper end 30 thereof. The opening up of the rope and the cross-sectional area of passageway 36 at such location will each be sufficient to permit the desired passage of an end strand S between strands S'. Larger rope can be spliced with equal facility merely by moving the same further downwardly of spike member 12 to a lower location thereon, since the larger rope is thereby not only opened up to the necessary greater extent, but additionally the cross-sectional area of passageway 36 is greater at such lower location. If an extremely large rope should not be opened sufficiently even when moved to the lower-most extremity of spike member 12, the requisite additional opening up thereof may be achieved by continuing to move it downwardly, onto and along base member 10. This is possible by reason of the heretofore-mentioned alinement of the edges 28, 32, 34 of spike member 12 with corresponding legs 18, 14, 16 of the base member. As the rope is moved downwardly of base member 10, the diverging legs thereof open and spread the rope to an ever-increasing extent in the same general manner as the edges of spike member 12. It will therefore be appreciated that splicing of even the very largest hawsers now in general use can be achieved by the present device.

Upon completion of a splicing operation, legs 14, 16 and cross-bar 20 of base member 10 may each be pivoted toward leg 18, thus reducing the device to a compact size convenient for transportation and/or storage.

It will thus be seen that there has been provided a rope-splicing device realizing the objects and possessing the benefits hereinbefore noted, together with many practical advantages. While in the drawing and specification there has been set forth a preferred specific embodiment of the invention, this was for purposes of description and illustration only, and not for purposes of limitation, the scope of the invention being defined in the claims.

That which is claimed is:

1. A rope-splicing device comprising:
  - (a) a base member adapted to stand upon a supporting surface;
  - (b) a spike member mounted in a substantially upright position upon said base member and having a pointed upper end upon which the rope is adapted to be impaled;
  - (c) said spike member being tapered and having three peripheral edges extending downwardly from said pointed upper end thereof in diverging relationship to each other for spreading open the impaled rope as the same is moved downwardly of said spike member;
  - (d) said spike member having a longitudinally-extending passageway of increasing cross-sectional area from said upper end to the lower end thereof, and the space between two of said edges of said spike
